CARL JAEK, OF BERN, SWITZERLAND, ASSIGNOR OF ONE-FOURTH TO UNITED PIECE
DYE WORKS, A CORPORATION OF NEW JERSEY.

PRINTING BLOCK OR CYLINDER.

Application filed May 7, 1924, Serial No. 711,542, and in Switzerland June 26, 1923.

This invention relates to printing cylinders and printing blocks and processes for producing them, and is especially directed to the manufacture of sand-blasted rubber faced 5 printing cylinders and printing blocks.

According to the present invention a rubber mass, which may be like ebonite, is vulcanized to a foundation, as of light metal, so as to furnish a suitable printing surface for 10 taking the place of the stone or metal materials now in use. A suitable cylinder core or flat plate as of aluminum is roughened where it is to receive the rubber mass and there is applied to it as by rolling a suitable thickness 15 of the compounded rubber. I have found that the compounded rubber may be prepared by mixing suitable rubber, with an equal weight of a suitable solvent such as benzol or carbon disulphide, adding a proper filler, 20 as hereinafter described, kneading the mass and adding sulphur, with or without a suitable amount of a rubber accelerator, such as lead oxide, paranitrosodimethylaniline, piperidine or anthraquinone.

I have found that a printing surface to be used for oil printing is obtained by mixing 30 parts of rubber, 30 parts of solvent, 65 to 70 parts of talcum, flour (wheat, corn or potato) or zinc oxide, and kneading them into a plastic 30 mass to which is added 10 to 30 per cent (on the dry material) of sulphur. For glue printing I have found that the best printing surface is obtained when kaolin or chalk is used in place of talcum, flour or zinc oxide in 35 about the same proportion.

For vulcanizing it the mixture is heated to a suitable temperature for a length of time depending upon the kind and amount of accelerator used. From one to six hours at a 40 maximum temperature of 170° to 180° C. has been found satisfactory. When the rubber is properly vulcanized in place upon the metallic or other backing it will be firmly fixed thereto when cold.

The cylinder or printing block thus prepared is then turned or planed and polished. This makes it suitable for attaching the pattern which may be a sized paper. It may then be placed in an automatic sand-blasting 50 apparatus which cuts away the unprotected

parts, thus engraving the pattern to any required or desired depth. A pattern or block thus prepared may weigh about one-third the weight of the cylinder or block hitherto used for the same work. Such a block not only 55 resists acid and water and many kinds of oils but is strong enough for intaglio printing. Where a rubber coating of suitable thickness is thus provided a cylinder or block may be reused by turning it or planing it down so 60 as to obtain a fresh surface on which a new design may be sand blasted. This may be done repeatedly.

In the accompanying drawing is shown one form of engraved printing cylinder, wherein 65 a metal backing *a* supports a hard rubber body *b*, on the surface of which are the intaglio lines *c* of the pattern to be printed, the lines *c* having been cut by a sand blast.

Having thus described certain embodiments 70 of my invention what I claim is:

1. The process of making printing surfaces which consists in vulcanizing a suitable rubber material and then sand blasting the surface. 75

2. The process of making printing surfaces which consists in vulcanizing a suitable rubber material to a backing so that an ebonite-like surface is produced, and then sand blasting the surface. 80

3. A printing block having a sand-blasted rubber face, and a non-resilient backing to which the rubber is vulcanized.

4. A printing block having a sand-blasted rubber face, and a metallic backing to which 85 the rubber is vulcanized.

5. A printing block having a sand-blasted rubber face, and an aluminum backing to which the rubber is vulcanized.

6. A printing block comprising a non-resilient back, a layer of rubber adapted to be engraved by sand-blasting and vulcanized thereto. 90

7. A printing block comprising a hard rubber face, a design cut thereon by sand-blasting, and a metallic backing securely secured throughout its entire surface to the rubber. 95

In testimony whereof, I have affixed my signature to this specification.

CARL JAEK.
